CLAIM

The ornamental design for a fire pit as shown and described.

DESCRIPTION

FIG. 1 is a front perspective view from above of the claimed fire pit according to the claimed design;

FIG. 2 is a front view from below of the claimed design of FIG. 1;

FIG. 3 is a rear view of the claimed design of FIG. 1;

FIG. 4 is a left side view of the claimed design of FIG. 1;

FIG. 5 is a right side view of the claimed design of FIG. 1;

FIG. 6 is a top view of the claimed design of FIG. 1;

FIG. 7 is a bottom view of the claimed design of FIG. 1; and,

FIG. 8 is a front perspective view of the claimed design of FIG. 1 in an alternate position.

The broken lines shown in the drawings are included for the purpose of illustrating portions of the fire pit that form no part of the claimed design.
